UNITED STATES PATENT OFFICE.

GUSTAV ABRAMS AND NILS NILSON, OF DASSEL, MINNESOTA.

VALVE-GEAR FOR ENGINES.

SPECIFICATION forming part of Letters Patent No. 317,071, dated May 5, 1885.

Application filed February 14, 1885. (No model.)

To all whom it may concern:

Be it known that we, GUSTAV ABRAMS and NILS NILSON, of Dassel, in the county of Meeker and State of Minnesota, have invented 5 certain new and useful Improvements in Valve-Gears for Steam-Engines, of which the following is a specification.

Our invention relates to steam-engines; and it consists in a novel construction of the valve-gear, as hereinafter fully set forth.

In the drawings, Figure 1 is a side elevation of an engine provided with our improved valve-gear. Fig. 2 is a vertical section of the same, taken on the line *xx*. Fig. 3 is a longitudinal section through the cylinder and steam-chest; Fig. 4, enlarged face view of the trip mechanism.

The object of our invention is to render positive, prompt, and sensitive the action of the 20 automatic cut-off device; and to this end it consists in providing the steam-cylinder with two independent small steam-cylinders (communicating with the steam-chest) having pistons, which, through the action of the governor and a rocking lever, actuate the rocking-cut-off valves.

A indicates the frame or bed of the engine; B, the main cylinder, provided with piston C, having rod D; E, the steam-chest, and F the 30 slide-valve therein, having rod or stem G.

Between the main cylinder B and the steam-chest, at the ends, are the rocking cut-off valves H I, the former provided with ports 1 2 3, and the latter with ports 4 5 6, as shown 35 in Fig. 3.

The steam-chest is provided with steam-inlet ports 7 8, outlet-ports 9 10, and exhaust-space 11, while the main cylinder is provided with corresponding ports, 12 and 13.

Upon one side of the main cylinder are the 40 cylinders J, each of which, as shown in Fig. 2, communicates at its upper end with the steam-chest E, and is there provided with a valve, a, which, by means of its threaded spindle a', can be adjusted to vary the amount of steam admitted to the cylinder J.

Upon the outer face of the cylinders J are cast or bolted the lugs or guides b, while the interior of each cylinder is bored out to receive a piston, c, suitable packing boxes or glands, c', being provided at the lower ends of the cylinders, as shown in Figs. 1 and 2.

The pistons c have attached to their lower ends arms or rods d, the hooked ends d' of which pass beneath and are guided by the lugs or guides b upon the side of the cylinder J, said arms or rods d being in turn connected near their lower ends with rods e, attached to the crank-arm e' on the stems of the rocking valves H I, as shown in Fig. 1.

The slide-valve rod G is connected by a link, G', to one end of the rocking arm or lever K, pivoted at b' on the frame or bed A, the upper end of the lever being provided with a slot, b², and connected by a rod, b³, with an eccentric, b⁴, on the engine-shaft b⁵, as shown in Fig. 1. By adjusting the rod b³ in the slot b² the throw of the slide-valve can be accurately regulated and controlled. The slide-valve serves merely to provide for, regulate, and 70 control the exhaust, but exercises no influence whatever upon the admission of steam, its ends being cut off, so that it does not cover the inlet-ports.

L indicates a rocking arm or lever, of Y form, 75 which swings or rocks upon a pivot-pin, f, on the side of cylinder B, the lower arm, f', of the lever L being slotted, as at f², (by which the throw of the lever may be varied,) and connected by a rod or pitman, f³, with the 80 lower end of the rocking lever K.

At opposite sides of the pivot f of the lever L, and swiveled in said lever, are guides or studs f⁴, the pivot f and the guides f⁴, each being provided with a transverse hole for the 85 purpose hereinafter specified.

At opposite extremities of the rocking lever L are dogs or latches g, pivoted at g', and provided with upper squared ends, g², and tail or extension g³, the movement of the dogs or latches being limited in one direction by the stops or lugs g⁴, and toward which they are pressed by the spring g⁵, secured to the lever L and bearing at either end upon the lower ends or tails g³ of the dogs or latches g, as shown 90 in Figs. 1 and 4.

M is the governor, and h its shaft, having its lower end stepped in the bed or frame A, and provided with bevel-gear h', which latter receives motion from the engine-shaft b⁵ through the bevel-gears h² h³ h⁴ and rod h⁵, journaled in bearings on the frame A, and carrying at its opposite ends the gear h² h³. The governor has attached to its collar i a slide, i², which terminates 100

in a stem, i^3 , passing vertically through the stationary pivot f , the slide i^2 being provided on opposite sides, at its lower end, with pivoted arms or trips i^4 , which pass through the semi-rotary or oscillating guides or studs f^4 , as shown in Figs. 1 and 4. It will be thus seen that the governor-slide i^2 can rise or fall while the rocking lever L oscillates or swings upon its pivot f .

The lower ends of the pistons e are spread out or enlarged to form feet c^2 , as shown in Figs. 1 and 2, which are adapted to descend upon the rubber or other suitable elastic buffers, c^3 , seated in sockets c^4 , in order to relieve the engine and the valve of the jar incident to the operation of the pistons c .

Upon reference to Fig. 3 it will be seen that the piston c has just completed its stroke and is ready to move in the opposite direction; that the slide-valve F has nearly completed its movement, that the valve H has completed its movement to allow the complete exhaust through ports 12 3 2 9 11, while the valve I has not moved sufficiently to allow the inlet 25 of steam through ports 8 4 6 13.

The operation of the device is as follows: Through the medium of the rocking lever K the rocking or swinging lever L is moved simultaneously with the slide-valve F , which 30 valve serves to connect one and the other end of the cylinder alternately with the outlet 11, the pivoted latches g of the lever L engaging alternately with hooked ends d' of the rods d , and thus elevating the pistons e . The upward movement of the piston e and rod d causes a similar movement of the rod e , connected to the rocking valves H I , and oscillating said valves in one or the other direction, according to the direction of oscillation of lever L . When the lever L is thus rocked upon its pivot f , and the engine is not using steam expansively, the trips i^4 , attached to the governor-slide i^2 , do not come into contact with the tails g^3 of the latches or dogs g until the 45 piston has completed or nearly completed its stroke. When the piston has completed its stroke, these trips i^4 , which pass through the oscillating guides f^4 , but which remain at a nearly uniform elevation, form an abutment, 50 against which the tails g^3 of the pivoted dog g strikes, and which depress their lower ends, thus throwing the upper squared end, g^2 , out of engagement with the hook d' of the rod d . As soon as the piston e is thus released the 55 steam, acting upon its upper end, forces it down, and thus reverses the rocking valve H or I as the case may be. During all this time the steam in the other cylinder J will have forced its piston down to its lowest position, carrying with it the hooks d' of rod d , which is brought in position to be struck and carried upward by the dog g , when the lever L rocks in the opposite direction. When the lever L oscillates, the dog g will ride over the 60 hook d' , and the spring, acting upon the tails, throws the tails up and the upper squared ends outward in engagement with the hooks d' .

Should the engine assume an excessive speed, the governor-collar i and slide i^2 would be depressed a slight distance, and thus project the trips i^4 through the oscillating or semi-rotary studs f^4 a corresponding distance. This action, as will be seen upon reference to Figs. 1 and 4, will cause the tripping of the latches g , and consequent cutting off of the steam by valves H I , at a period somewhat sooner than would be done were it not for the too great speed of the engine.

Having thus described our invention, what we claim is—

80

1. In a steam-engine, the combination of a main steam-cylinder, a piston movable therein, a slide-valve adapted to connect the exhaust-ports of the cylinder with the steam-outlet, a cut-off or regulating valve between the steam-chest and cylinder, a supplemental steam-cylinder communicating with the steam-supply, and a piston mounted in said supplemental cylinder, connected with the cut-off valve, and adapted to impart motion thereto, substantially as explained.

90

2. In a steam-engine, the combination of a main steam-cylinder, a piston movable therein, a main valve adapted to connect the exhaust-ports of the cylinder with the steam-outlet, a cut-off valve between the steam-chest and cylinder, a supplemental cylinder communicating with the steam-supply, and a piston mounted in said supplemental cylinder, connected with the cut-off valve, and adapted to impart motion thereto in one direction, and a lifting device connected with a moving part of the engine, and adapted to move the piston and valve in reverse directions.

95

3. In a steam-engine constructed substantially as shown and described, the combination of cylinder B , steam-chest E , rocking valves H I , between the steam-chest and cylinder, provided with suitable ports, rocking lever L , provided with dogs g , cylinders J , communicating with the steam-chest, provided with pistons connected with the rocking valves, and having hooks and mechanism, substantially such as shown, for rocking the lever L .

105

4. In a steam-engine, the combination of cylinder B , piston C , steam-chest E , valve F , rocking valves H I , between the cylinder and steam-chest, cylinder J , pistons c therein, provided with hook d' , and connected with and adapted to rock the valves H I , governor M , provided with slide i^2 , having arms i^3 i^4 , rocking lever L , provided with studs f^4 , dogs g , and spring g^5 , and an intermediate connection between the engine-shaft and the lever L , for 110 rocking the latter alternately in reverse directions.

115

5. In a steam-engine, the combination of cylinder B , piston C , steam-chest E , slide-valve F , provided with rod G , rocking valves H I , an actuating mechanism for said valves, constructed substantially as described and shown, rocking lever K , connecting the slide-valve rod and the actuating mechanism and

120

125

130

driven by an eccentric, b^4 , on the main-shaft b^5 , as and for the purpose set forth.

6. In a steam-engine, the combination of cylinder B, piston C, steam-chest E, slide-valve F, rocking valves H I, cylinders J, communicating with the steam-chest, provided with pistons e for operating the valves H I in one direction, and a rocking lever actuated by the main shaft for raising the piston e and thereby rocking the valves in the reverse direction.

7. In a steam-engine substantially such as shown and described, the combination of cylinder B, steam-chest E, rocking valves H I, 15 rocking lever L, provided with dogs g for tripping the valves H I, and with oscillating studs f^4 , and governor-plate i^2 , provided with trips i^4 , passing through the studs f^4 , as and for the purpose set forth.

20 8. In a steam-engine substantially such as shown and described, the combination of cyl-

inder B, steam-chest E, piston C, slide-valve F, rocking valves H I, cylinders J, communicating with the steam-chest, pistons e within the cylinders, connected with the rocking 25 valves and provided with hooks d' , rocking lever L, provided with dogs g, and mechanism for rocking the lever L alternately in reverse directions.

9. In a steam-engine, the combination of cylinder B, piston C, steam-chest E, slide-valve F, rocking valves H I, cylinders J, pistons e within the cylinders, provided with hooks d' , and connected with the valves H I, 30 rocking lever L, provided with dogs g, spring g^6 , and studs g^4 , and mechanism for rocking the lever L alternately in reverse directions.
